OHIO, A CORPORATION OF OHIO.

AUTOMATIC SHUT-OFF VALVE.

1,139,462.

Specification of Letters Patent. Patented May 11, 1915.

Application filed June 22, 1914. Serial No. 340,564.

To all whom it may concern:

Be it known that we, HARRISON H. SOUTHWORTH and GEORGE A. GASE, citizens of the United States, residing at Cleveland, in the county of Cuyahoga and State of Ohio, have invented a certain new and useful Improvement in Automatic Shut-Off Valves, of which the following is a full, clear, and exact description, reference being had to the accompanying drawings.

This invention relates to controlling valves and particularly for a valve adapted to be interposed in a passage for fluid leading to a receptacle to control the flow of such fluid to the receptacle, being dependent for its operation on the pressure within said receptacle.

In the particular embodiment shown herein, this invention is adapted for use in connection with a refrigerating apparatus of a type described in the application of Mr. Harrison H. Southworth, No. 732,807, filed November 22, 1912. In this application is described a system in which practically all of the refrigerant is driven off from the generator-absorber to a condenser during the period of generation, and all of the refrigerant passes from the condenser through the refrigerating coils back to the generator-absorber during the period of absorption.

Our shut-off valve is preferably interposed in the passage leading from the condenser through the refrigerating coils to the absorber, and is adapted to be controlled by the pressure in the generator-absorber, having a passage connecting it therewith.

An object of the invention is to provide such a valve which shall be entirely automatic and efficient in its operation and which shall be simple in construction, while being thoroughly tight.

Another object is to provide a valve which is normally held open by spring pressure to permit the passage of liquid under pressure, from the condenser to the absorber, the valve being insured against closing by the pressure of such liquid but which may be closed by the pressure in the generator-absorber rising to a point sufficient to overcome the spring pressure and the pressure in the passage leading from the condenser.

Another object is to conveniently arrange the valve so that it may be operated under

the desired relative pressures; this we accomplish by providing two diaphragms of different areas, the smaller one of which is acted upon by the pressure of the condenser while the valve is opened, and the larger of which is acted upon by the pressure of the generator, to close and hold the valve in closed position.

Other objects of our invention will become apparent in the following description and the essential characteristics are set forth in the claims.

Figure 1 is a vertical central section of our valve; Fig. 2 is a section of our valve on the line 2-2 of Fig. 1; Fig. 3 is a detail of the flat spring; Fig. 4 is a detail of the valve plug.

As shown, the valve housing comprises two casings suitably connected by threaded members. The upper casing for the valve proper comprises two chambered shells 10 and 11, clamped together at their margins by suitable bolts 12 and embracing between them a metal diaphragm 14. The upper shell 10 is provided with an axial passage 16 communicating with the exterior of the casing and with the chamber 15, formed between the diaphragm 14 and the shell 10. This passage has an enlarged inner portion 17, forming a shoulder which provides a seat adapted to be closed by the tapered end 21 of the valve 20. This valve is slidably mounted in the passage 17 and is provided with a groove as at 22, to allow a communication between the passage 17 and the chamber 15, and is flanged at its lower end to form a head, the lower face of which abuts the diaphragm 14. Interposed between the upper shoulder of this head and the upper face of the chamber 15, is a leaf spring 25, surrounding the valve stem and tending normally to open the valve. Beneath the diaphragm is shown a bearing block 26, which is used merely to simplify the manufacture and to form a flat surface limiting the depression of the diaphragm. The liquid flows through the passage 16, past the valve plug, when open, and from a passage 24. The lower casing also comprises two chambered shells 30 and 31 clamped together at their margins by suitable bolts 32, and embracing between them a metal diaphragm 34. The lower shell 31 is provided with a nipple 33 adapted to be

connected by a suitable coupling to a by-pass pipe which is in turn connected to the generator-absorber, so that at all times the lower side of the diaphragm 34 is exposed 5 to the pressure in the generator-absorber. As shown, this diaphragm is of sufficiently greater area than the diaphragm 14 to close the valve against the action of the springs 25 and 38 (hereinafter described), when 10 the pressures above the diaphragm 14 and below the diaphragm 34 are equal and somewhat above atmospheric.

To transmit the upward movement of the diaphragm 34 to the valve 20, we have provided 15 a pin 35, slidably journaled in the shell 11 and the block 26, with the upper end abutting the diaphragm 14 directly beneath the valve 20, and the lower end having a threaded engagement with the center 20 of a disk 36, which abuts the upper side of the diaphragm 34 and bears over a major portion of its area. Interposed between the lower face of the upper shell 11 and the upper face of the flange 36, and surrounding 25 the pin 35, we have provided a coiled compression spring 38 tending to depress this diaphragm. The chamber formed between the diaphragm 34 and the shell 30, is provided with a vent 40 communicating 30 with the atmosphere.

In use, the passage 16 of the upper shell 10 is connected by a suitable coupling with a line pipe leading to the condenser, and the opening 24 communicates with a line 35 pipe passing to the refrigerating coils. Thus it will be seen that the exposed upper end of the valve 20 is at all times subjected to the pressure of the liquid refrigerant in the condenser tending to open the valve 40 and, when the valve is open, the pressure of the liquid is communicated to the chamber 15 and so acts on the upper face of the diaphragm 14, tending to depress the same. When the valve is open, it will be seen that 45 the liquid refrigerant has a clear passage from the condenser through the passages 16, 17 and 25 to the pipes leading to the coils.

It will be noted that each of the diaphragms form one wall of the chambers communicating with their respective passages, and as these diaphragms are firmly gripped at their peripheries between the members of the casing and are held between 50 suitable packing members, the chambers in communication with the passages are thoroughly liquid tight. This is particularly important in the construction in the upper casing in connection with the 55 valve, as it enables the liquid to pass the valve without allowing it to escape from the casing, it being very difficult to provide means exterior to the casing for closing this valve, which would not be liable 60 to permit leakage.

The operation of our shut-off valve is as follows: During the period when the generator-absorber is acting as a generator and the condenser is being cooled, it is necessary in order to cause the vapor to enter the 70 condenser that the pressure in the generator be somewhat in excess of the condenser pressure. This pressure in the generator, transmitted through a by-pass pipe to the lower side of the diaphragm 34, is sufficient 75 to force the diaphragm 34 upward against the combined pressures of the condenser pressure acting on the diaphragm 14, and the pressure of the springs 25 and 38, and so close the valve 20 and hold it closed 80 throughout the cycle of generation. At a predetermined degree of low saturation in the generator, the cycle of operation is reversed and the generator being cooled acts 85 as an absorber. At some point, the pressure in the generator-absorber is decreased to such an extent that the high pressure of the liquid refrigerant in the condenser acting on the conical face 21 of the valve 20, in addition to the pressure remaining in 90 the chamber 15 on the valve side of the diaphragm and the pressure of the springs 25 and 38, is sufficient to open the valve, allowing the condenser pressure to be transmitted to the chamber 15 and act on the upper side 95 of the diaphragm 14 to retain the valve in an open position. The liquid refrigerant then passes through the passage 24 into a pipe and is carried to the refrigerating coils. During this cycle of operation, it is of 100 course necessary that the pressure in the generator-absorber be considerably less than the pressure in the condenser. When all of the liquid refrigerant in the condenser is vaporized, the cycle of operation is again 105 automatically changed, and heat is applied to the generator. As the generator is heated, the pressure therein rises, and is exerted through a by-pass pipe, upon the lower side 110 of the diaphragm 34 as above described, closing the valve 21.

It will be seen from the foregoing description that we have provided a simple efficient valve, which will accomplish the purposes hereinbefore set forth and when 115 used in connection with a refrigerating machine, such as mentioned, will act automatically to close during the period of generation, and to automatically open during the period of absorption, thereby controlling 120 the passage of the liquid refrigerant in synchronism with the cycle of operation of the refrigerating machine.

Having thus described our invention, what we claim is:

1. In a device of the character described, the combination of a pair of casings each comprising two members clamped together, one of said casings having a central extension by which it is connected directly to the 130

other, each casing having an internal chamber in which is a diaphragm, a distance piece slidably mounted in said extension and bearing against two diaphragms, a spring 5 tending to force one of the diaphragms away from the other, a valve plug in the opposite side of said other diaphragm, a spring acting directly on the valve plug and tending to move it toward its diaphragm, 10 passages to and from the space occupied by the valve plug, a passage to the opposite side of the other diaphragm, and a passage to the atmosphere from the other side of the chamber occupied by the last named dia- 15 phragm.

2. In a device of the character described, the combination of a two-part casing having an internal chamber, a diaphragm extending across said chamber, a second two- 20 part casing having a smaller internal chamber, a diaphragm extending across the lat-

ter chamber, said second casing being secured to the first casing and having a flat surface adjacent to its diaphragm on the side toward the larger diaphragm and comparatively close to the smaller diaphragm, a slidably distance piece between the diaphragms, and a valve plug abutting the smaller diaphragm on the side opposite the distance piece and controlling a passage 25 adapted when the plug is away from its seat to communicate with the chamber on the valve side of the small diaphragm.

In testimony whereof, we hereunto affix our signatures in the presence of two witnesses. 30
